UNITED STATES PATENT OFFICE.

JAMES DAMEY AND WILLIAM H. CORK, OF CHICAGO, ILLINOIS, ASSIGNEES
OF ONE-THIRD TO N. S. BOUTON, OF CHICAGO, ILLINOIS.

HEATER.

SPECIFICATION forming part of Letters Patent No. 700,745, dated May 27, 1902.

Application filed July 18, 1901. Serial No. 68,199. (No model.)

To all whom it may concern:

Be it known that we, JAMES DAMEY and WILLIAM H. CORK, citizens of the United States, residing at Chicago, in the county of Cook and State of Illinois, have invented a new and useful Improvement in Heaters, of which the following is a specification.

Our invention relates particularly to heaters which are provided with a hot-water or steam heating-circuit and with a separate hot-water-supply circuit, the latter for supplying baths, lavatories, &c.

Our primary object is to provide a heater of improved construction having very high heating capacity and possessing many other features of advantage, as hereinafter described and claimed. In the preferred construction there are employed a heating-circuit wherein the heating fluid is maintained at a given temperature, a hot-water-supply circuit wherein water is ordinarily maintained at a higher temperature, and a separate low-level heating-circuit available for heating at low levels.

Our invention is illustrated in its preferred form in the accompanying drawings, in which—

Figure 1 is a central vertical section parallel to the sides of the heater, the section being taken as indicated at line 1 of Fig. 2; Figs. 2 and 3, transverse sections taken as indicated at the corresponding lines of Fig. 1; Fig. 4, a section similar to Fig. 1, but showing the inner wall of the outer flue of the heater in elevation; Figs. 5, 6, 7, 8, 9, and 10, sections on a reduced scale and taken as indicated at the corresponding lines of Fig. 2; Fig. 11, a section, on a reduced scale, taken as indicated at line 11 of Fig. 1; Fig. 12, a broken view showing the base and grates of the heater viewed as indicated by the arrow at line 12 of Fig. 2, and Fig. 13 an enlarged broken horizontal section showing the connection between the rear section and a side section of the outer wall of the outer flue.

The preferred construction is as follows: 1 represents the heater-base, Fig. 12, upon which are mounted a circular grate 2 and a coacting grate 3, suitably concaved at its front portion to serve the grate 2; 4, the outer wall

or casing of the heater, which constitutes also the outer wall of the outer flue 5 and which has a removable rear section 6; 7, a fuel-magazine which depends from the upper portion of the heater and is located above the center of 55 the grate 2, said magazine having, Fig. 9, an inner wall 8, an outer wall 9, peripheral vertically-disposed water-legs 10, radially-arranged hollow stubs or headed pipes 11 at the front portion of the magazine, and a lower 60 central chamber 12, Fig. 1, separated from the upper portion of the chambered magazine by a partition 13; 14, Fig. 11, an outer water-chamber comprising two curved sections 15 and 16, meeting in a vertical plane at the 65 front portion of the heater, and a flat rectangular rear section 17, meeting the sections 15 and 16 in a vertical plane at the rear portion of the heater; 18, Fig. 3, a steam or hot-water dome communicating with the 70 water-chamber 14 through pipes 19, Figs. 3 and 6; 20, passages or communications between the dome 18 and the adjacent upper ends of the water-legs 10; 21, Figs. 2 and 8, flue-passages through the two side water-legs 75 10, at the upper portion thereof; 22, a baffle-plate which covers the rear portion of the outer or return flue 5, as illustrated in Figs. 4 and 7, said baffle-plate ending in downwardly-extending partitions 23, which divide 80 the outer flue vertically, Fig. 9; 24, an upward extension for the magazine 7, formed in the dome 18, as illustrated in Figs. 1 and 2; 25, a flue leading from the upper portion of the magazine extension or chamber 24 through 85 the dome 18 to the smoke-stack 26 at the rear of the heater, a damper 27 being interposed between the flue 25 and said smoke-stack; 28, a branch pipe or flue connecting the smoke-stack 26 with the flue 5 beneath the baffle-plate 22, said branch pipe being equipped with a damper 29; 30, a cold-water or return pipe having branches 31 and 32, the latter in turn having branches 33 and 34, the branches 31 and 34 serving to supply water to the outer 95 chamber 14 and the branch 33 serving to supply water to the chambered reservoir 7 above the partition 13; 35, a pipe through which the circuit of the chamber 14 is supplied, said pipe usually having connection with a reser- 100

voir (not shown) and a valve 36 being provided through which water is admitted to replenish the water of the circuit when desired; 37, a pipe communicating with the branch pipe 31 and with the steam-dome 18 and equipped with a sight-glass 38 and a pressure-gage 39, said pipe being available when it is desired to employ the circuit of the chamber 14 as a steam-circuit; 40, a steam-chamber communicating with the dome 18 and provided internally, Fig. 1, with a diaphragm 41, which serves to actuate a lever 42, connected through the medium of a rod 43 with a draft-regulating door 44 and connected also through the medium of a rod 43^a with a draft-check door 43^b; 45, a hot-water or steam pipe, as the case may be, having branch connections 46 and 47 with the dome 18; 48, Figs. 1 and 4, a supply-pipe communicating with the chamber 49, formed in the back section 17 of the outer water-chamber 14, said chamber 49 being separated from the remainder of the back section by a partition 50; 51, an outlet or hot-water pipe for the chamber 49, the same being equipped with a valve 52; 53, a branch pipe connecting the chamber above the partition 50 with the pipe 51 inside the valve 52, said pipe 53 being equipped with a valve 54; 55, Figs. 3 and 7, a cold-water or return pipe for the chamber 12; 56, a hot-water or outgoing pipe for the chamber 12, said pipe being connected through the medium of a branch pipe 57, Fig. 1, equipped with a valve 58, with the dome 18; 59, Fig. 1, a fuel-chute leading to the chamber 24; 60, Figs. 1 and 11, an inner fire-pot removably connected with the lower end of the fuel-magazine, and 61 a removable chute leading through the outer water-chamber 14 to said removable fire-pot.

40 The branch pipes 31 and 34 are equipped with valves 62 and 63, respectively, and the branch pipe 33 is equipped with a valve 64. The back section 17 of the outer water-chamber 14 is equipped on its inner side with headed pipes or hollow stubs 65, as shown in Figs. 3 and 7. These pipes are arranged on opposite sides of the rear water-leg 10 and are of varying lengths in order to conform to the shape of the inner water-chamber, as shown in Fig. 8. Fig. 1 illustrates the manner in which the grate 2 is pivoted at its center in order to oscillate in a horizontal plane. Fig. 12 illustrates the manner in which the grate 3 is journaled to permit it to be swung on a horizontal shaft 66. The manner in which the sections 15, 16, and 17 of the outer water-chamber 14 are detachably joined together is clearly shown in Fig. 11, where are shown lugs on the several sections and bolts connecting said lugs. The base 1 is shown in Fig. 12 to be provided near its periphery on its upper surface with flanges 1^a and 1^b, inside the former of which the lower end of the outer water-chamber 14 is located and outside the latter of which the lower end of the outer casing 4 is located.

The manner in which the rear section 6 of

the casing 4 is made removable is clearly shown in Fig. 13, where the rear section 6 is shown equipped with angle-irons 67, which are detachably joined by screws 68 to the adjacent portions of the sides of the casing. As shown in several of the figures, the lever 42 is pivoted at 69 and is provided with an adjustable weight 70, through which the action of the lever is controlled.

From the foregoing description the manner of operation will be readily understood. Chamber 12 at the base of the fuel-magazine being located near the hottest portion of the fire readily serves, though of a small size, to supply as much highly-heated water as is usually desired from a heater of this kind. The remaining water-chambers of the heater, with the exception of the chamber 49 at the lower portion of the back section 17 of the outer water-chamber, are all connected and serve to supply water at the desired temperature to the radiators. The water-chamber 49 may serve to supply water at a comparatively low level where required, as for greenhouse purposes.

During those seasons of the year when little or no heat is required for the heating-circuit and it is still desired to have a hot-water supply for the baths and lavatories the inner fire-pot and the chute 61 may be put in place, as illustrated in Fig. 1. The damper 27 being left open and the damper 29 closed, as illustrated in Fig. 1, the draft is directly through the fuel-magazine, and the fire is confined to a small portion of the grate, the fuel being charged in through the chute 61. During such use of the heater the outer chambers and walls of the heater serve to prevent radiation of the heat into the room where the heater is located.

For winter service the fire-pot 60 and chute 61 are removed, the damper 27 closed, and the damper 29 opened. The chamber 49 at the base of the back section 17 of the outer water-chamber 14 may or may not be connected with the general heating-circuit. Assuming the valve 54 to be closed and the valve 52 to be open, the low-level circuit would be disconnected from the main heating-circuit and water would flow through the low-level circuit, as indicated by the arrows in Fig. 1. Assuming the valve 52 to be closed and the valve 54 to be open, the water from the chamber 49 would circulate through the main heating-circuit. With the heater arranged as last suggested the fuel-magazine is kept charged through the chute 59. The draft is then upward between the inner water-chamber and the outer water-chamber among the water-legs 10 and the horizontal water-pipes 11 and 65 till the dome 18 is encountered, and thence downward through the front portion of the flue 5, past the lower ends of the vertical partitions 23, and upwardly through the rear portion of the flue 5 to the branch pipe 28. Such products of combustion as pass upwardly at the rear portion of the heater and

- encounter the dome are forced to pass forwardly through the flues 21 and available spaces between the upper portions of the side water-legs 10 and adjacent portions of the outer water-chamber 14, after which they pass downwardly outside the outer wall of the outer water-chamber 14 and through the front portion of the flue 5 till they pass the lower ends of the partitions 23, whence they 5 pass to the branch pipe 28. The draft-door 44 and the check-door 43^b, being connected with opposite ends of the lever 42, move in opposite directions, so that when the draft is opened the check is closed, and vice versa. 10
- 15 In the first adjustment the draft-door will be left open as much as is desired and the weight 70 so located as to permit the lever to operate only when a certain degree of heat is reached. When the diaphragm 41 is forced 20 upwardly by steam-pressure, the result is to raise the check-door 43^b and lower the draft-door. The heater is properly arranged and equipped to permit the main heating-circuit to be operated as a steam-circuit instead of a 25 hot-water circuit. Such a conversion can be accomplished merely by supplying less water to the boiler and maintaining the water within required limits by reference to the water-gage 38.
- 30 Changes in details of construction within the spirit of our invention may be made. Hence no limitation is to be understood from the foregoing detailed description except as shall appear from the appended claims.
- 35 What we claim as new, and desire to secure by Letters Patent, is—
1. In a heater, the combination of a suitable base, an outer casing, an outer water-chamber within said casing and separated therefrom 40 by a flue-space, said casing and outer water-chamber having corresponding removable vertical sections at one portion thereof, an inner water-chamber, a central fuel-magazine, and draft-regulating means.
  2. In a heater, the combination of a suitable base, an outer casing having a curved front, substantially tangential sides, and a removable rectangular rear section, an outer water-chamber separated from said casing by a flue-space, and having a removable rear section adapted 50 to be removed after removal of the rear section of the casing, an inner water-chamber, a fuel-magazine, and draft-regulating means.
  3. In a heater, the combination of a suitable base, an outer casing having a rectangular-shaped removable rear wall-section, an outer water-chamber separated from said casing by a flue-space and having a removable rear section provided with inwardly-projecting water-stubs, an inner water-chamber and fuel-magazine, and draft-regulating means.
  4. In a heater, the combination of a suitable base, an outer casing having a removable rear section, an outer water-chamber within said casing and separated therefrom by a flue-space, said water-chamber having a removable rear section provided with inwardly-projecting water-stubs, an inner water-chamber with which said stubs conform, and which is itself provided on its front side with water-stubs, and draft-regulating means.
5. In a heater, the combination of a suitable base, a circular grate oscillatory in a horizontal plane, an adjacent grate having a concavity receiving the adjacent portion of said circular grate and itself pivoted on a horizontal axis, an outer casing having a rectangular-shaped removable rear wall-section, an outer water-chamber having a rectangular-shaped removable rear section, said water-chamber being separated from said casing by a flue-space, a baffle-plate covering the rear portion of said flue, vertical partitions in said flue at the front ends of the forward projections of said baffle-plate, a smoke-stack connected 75 with said flue beneath said baffle-plate, an inner water-chamber between which and said outer water-chamber the products of combustion may pass upwardly, space being preserved to permit the products of combustion 80 to pass over the upper end of said outer water-chamber and downwardly through the front portion of said flue, a fuel-magazine, and draft-regulating means.
6. In a heater, the combination of a suitable 90 base, a superimposed casing provided with a rectangular-shaped rear section, a circular grate oscillatory in one plane, a grate oscillatory in another plane and suitably concaved to receive the adjacent portion of said circular grate, an outer water-chamber separated from said casing by a flue, a baffle-plate covering the rear portion of said flue, vertical partitions in said flue at the front ends of the forward projections of said baffle-plate, an 95 inner water-chamber and fuel-magazine, a smoke-stack having one communication with said fuel-magazine and another with said flue beneath said baffle-plate, dampers regulating the passages from the fuel-magazine and from 100 said flue to said smoke-stack, and a removable fire-pot located at the base of said magazine.
7. In a heater of the character described, the combination of a suitable base, a circular 105 grate and a coacting grate having a substantially straight rear edge, an outer casing having a removable rear section, an outer water-chamber separated from said casing by a flue-space, said water-chamber comprising two 110 curved sections connected at their front portions and a rear rectangular-shaped section connected with the rear portions of said first-named sections, an inner water-chamber and fuel-magazine, a baffle-plate covering the rear 115 portion of said flue, vertical partitions in said flue at the front ends of the forward projections of said baffle-plate and extending downwardly to near the base of the heater, space being preserved at the upper portion of said 120 outer water-chamber to permit gases to pass over said chamber into said flue at the front portion thereof, a smoke-stack connected 125 with said magazine and with the rear portion 130

of said flue beneath said baffle-plate, and dampers regulating the passages from said magazine and said flue to said smoke-stack.

8. In a heater, the combination of a suitable base, a suitable casing and a central fuel-magazine chambered to receive water, a lower chamber being provided for supplying one hot-water circuit, and an upper chamber for supplying another circuit.

9. In a heater, the combination of a base, a grate, an outer casing, an outer water-chamber separated from said casing by a flue, a baffle-plate covering the rear portion of said flue, vertical partitions in said flue and extending from said baffle-plate to near the lower portion of the flue, a dome located some distance above said outer water-chamber and in communication therewith, an inner water-chamber and fuel-magazine, said inner water-chamber being in communication with said dome, a smoke-stack communicating with said magazine and with the rear portion of said flue beneath said baffle-plate, and dampers regulating the passages from said magazine and said flue to said smoke-stack.

10. In a heater, the combination of a base, a grate, an outer casing, an outer water-chamber separated from said casing by a flue, a baffle-plate covering the rear portion of said flue, vertical partitions in said flue and extending from said baffle-plate to near the lower portion of the flue, a dome located some distance above said outer water-chamber and in communication therewith, an inner water-chamber and fuel-magazine, said inner water-chamber being in communication with said dome and divided horizontally to afford a separate chamber at its base, a heating-circuit connected with said dome, an independent hot-water-supply circuit connected with said last-named chamber, a smoke-stack having communication with said magazine and with said rear portion of the flue beneath the baffle-plate, and dampers controlling the passages from said magazine and said flue to said smoke-stack.

11. In a heater, the combination of a base, a casing provided with a removable rear section, an outer water-chamber separated from

said casing by a flue and having a removable rear section, said rear section having a horizontal dividing-wall affording an independent lower chamber, a baffle-plate covering the rear portion of said flue, vertical partitions depending from said baffle-plate, a dome located above said water-chamber, an inner water-chamber and fuel-magazine, a smoke-stack having communication with said magazine and with the rear portion of said flue beneath said baffle-plate, and dampers controlling the passages from said magazine and said flue to said smoke-stack.

12. In a heater, the combination of a base, a grate, an outer casing, an outer water-chamber separated from said casing by a flue, an inner water-chamber provided peripherally with vertically-extending water-legs and affording a fuel-magazine, a baffle-plate covering the rear portion of said flue, vertical partitions depending from said baffle-plate, a smoke-stack communicating with said fuel-magazine and with the rear portion of said flue beneath said baffle-plate and dampers controlling the passages from said magazine and said flue to said smoke-stack.

13. In a heater, the combination of a base, an outer casing, an outer water-chamber separated therefrom by a flue, a baffle-plate covering the rear portion of said flue, vertical partitions in said flue, a dome located above said water-chamber and communicating with said water-chamber, an inner water-chamber communicating with said dome, a separate water-chamber at the base of said inner water-chamber, pipes leading therefrom, a circuit connected with said dome, valved communication between one of said pipes and said dome, a separate water-chamber at the base of said outer water-chamber, circuit-pipes connected with said last-named separate water-chamber, and valved communication between said last-named separate water-chamber and said outer water-chamber.
